UNITED STATES PATENT OFFICE.

ERNESTO SASSENHOFF, OF NEW YORK, N. Y.

DESIGN FOR A PRICE-CARD HOLDER.

SPECIFICATION forming part of Design No. 26,461, dated December 29, 1896.

Application filed November 25, 1896. Serial No. 613,462. Term of patent 7 years.

To all whom it may concern:

Be it known that I, ERNESTO SASSENHOFF, a subject of the Emperor of Germany, residing at the city of New York, in the county 5 and State of New York, have invented and produced a new and original Design for a Price-Card Holder, of which the following is a specification, reference being had to the accompanying drawings, forming a part hereof, 10 and in which—

Figure 1 is a front view of the price-card holder bearing and incorporating my design. Fig. 2 is a back view of same. Fig. 3 is an end view of same, and Fig. 4 is a top edge 15 view of same.

The leading feature of my design consists of the form and configuration of the price-card holder, as shown in the accompanying drawings.

20 In the drawings, A designates the body of said price-card holder, which body is substantially oblong and in the form of a flat plate

having its four corners *a b c d* rounded. The body A has adjacent to its opposite ends the vertical slots *e c*, and the portions of the body 25 A adjacent to the upper ends of said slots are rounded, as indicated at *ff*, the curvature of the parts *ff* harmonizing with the curvature at the points *a b c d*. The plate or body A carries the springs B B, whose upper ends are 30 also rounded and whose lower ends curve outward from the plate A. At the lower edge of the plate A are the pointed lugs C.

What I claim is—

The design for a price-card holder, substantially as shown and described. 35

Signed at New York, in the county and State of New York, this 29th day of October, 1896.

ERNESTO SASSENHOFF.
